TUBE FRAME FOR AXMINSTER LOOMS

Oscar V. Payne, Leicester, Mass., assignor to
Crompton & Knowles Loom Works, Worcester,
Mass., a corporation of Massachusetts

Application December 20, 1937, Serial No. 180,805

5 Claims. (Cl. 139—10)

This invention relates to improvement in tube frames for Axminster looms and it is the general object of the invention to provide a strong durable connection between the tube frame and the transporting chain.

It has been customary heretofore to provide tube frames with end ears which are slotted for the reception of a chain engaging hook. By this construction the tube frame is supported by a relatively weak ear which may break if the load on the tube frame is increased. One of the objects of the present invention is to permit the use of a stronger and larger tube frame carrying an increased amount of tuft yarn and supported by ears and hooks which are much stronger than those heretofore used. This result I achieve by locating the hook entirely at one side of the ear so that the latter is not perforated.

20 Heretofore I have proposed a sliding hook having a rectangular support received by the tubular carrier bar of the tube frame. In the present invention I simplify this construction by using a cylindrical stud sliding in bearing endwise of the tube frame and hold the hook in proper alignment for engagement with the chain by a guide pin or the like extending through the ear. The guide pin is spaced from the axis of the cylindrical stud and therefore prevents turning of the hook about its stud and bearings in a plane transverse of the tube frame carrier bar.

It is desirable to be able manually to disconnect the tube frame from its chain and this can be accomplished very simply by depressing the guide pin which extends through and beyond the outer surface of the ear. By pushing the guide pin which is rigid with the hook the latter is moved inwardly away from the chain to permit detachment of the tube frame.

40 It is a further object of my invention to secure a hollow block to the bottom of the ear and insert the block into the hollow bar, after which the block is fastened to the bar.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a vertical longitudinal section through a tube frame and clutch made according to my present invention, parts of the structure being shown in elevation,

Fig. 2 is an end elevation taken in the direc-

tion of arrow 2, Fig. 1, the clutch being omitted.

Fig. 3 is a horizontal section on line 3—3 of Fig. 2.

Fig. 4 is a transverse vertical section on line 4—4 of Fig. 3 and

Fig. 5 is a perspective view showing the tube frame bracket detached from the carrier bar.

The tube frame set forth herein is designed for use in an Axminster loom of the type well known in the industry and only such parts thereof as affect the manipulation of the tube frame will be set forth. The loom will have at each end thereof a transporting chain 10 having outer and inner links 11 and 12, respectively, and also a transfer clutch 13 supported on an arm 14 by means of a gudgeon 15. The clutch is manipulated to effect wiping-in motions when the tube frame is in cloth forming position by a link 16 pivotally connected to the clutch as at 17. The chain will move by a step by step motion well understood and will come to rest periodically to permit the selected tube frame to be disconnected therefrom, moved toward the clutch, and returned to the chain.

My invention relates more particularly to the tube frame and comprises a metallic tubular bar 20 preferably of rectangular cross section, and having attached thereto a plurality of yarn tuft tubes 21. On the upper side of the bar 20 is a spool bearing 22 to receive a gudgeon 23 of a spool S on which will be wound the variously colored tuft yarns. The bearing may be held to the tube frame in any approved manner.

Projecting into the end of the tube is a hollow sheet metal block 25 having parallel vertical side walls 26 and 27, respectively, connected together at their inner ends by an end wall 28, and bridged by a bearing block 29. The latter may be secured to the walls 26 and 27 by means of screws 30 or in any other approved manner. The block 29 is provided with a bearing 31 of cylindrical form in alignment with a second bearing 32 located in the end 28. The bearings 31 and 32 are on the same axis, which is substantially parallel to the axis of the bar 20.

An ear 35 is notched as at 36 to receive the outer reduced ends 34 of the walls 26 and 27 to which the ear may be secured as by welding. The ear has an opening 37 aligning with the bearing 31 and said ear extends upwardly and may be slightly offset as at 38 to provide a tongue 39 for insertion between the links 11 and 12 of the transporting chain. The ear is rigid with respect to the block 25 and the latter is held to the tube frame bar as by a screw 40 and also by

screws 41 which pass through the bar 10 and walls 26 and 27 to be threaded into the solid block 29. In this way the hollow block 25 and the ear 35 are secured tightly to the carrier bar 20.

5 A hook 45 is so disposed as to lie entirely on one side of the ear, being located as shown in Fig. 1 between the spool and the ear. The hook has an upper bent end 46 to lie over the link 12 and has the lower end thereof riveted or otherwise fastened to a slide gudgeon or stud 47 having a large part 48 received by and sliding in the bearing 31. A reduced part 49 of the stud 47 extends inwardly and slides in the bearings 32, being surrounded by a compression 10 spring 50 located between the end wall 28 and the enlarged part 48. The purpose of the spring is to hold the hook normally in the position shown in Fig. 1 with the lower vertical part 51 of the hook extending along the corresponding 15 adjacent part of the ear 35. The hook may be offset as indicated in Fig. 1 but preferably does not pass through any part of the ear.

The stud 47, being cylindrical, would be free to turn in its bearings 31 and 32, and in order 20 to prevent this I secure a guide pin 55 to the hook at a point below the end 46. The guide pin passes through a hole 56 in the ear and is spaced sufficiently below the chain to permit the customary upward motion of the tube frame 25 necessary to permit the hook end 46 to slide over the highest part of the chain link 12. When the tube frame is in an inverted position shoulders 60 of the ear may be relied upon to engage the single links 61 of the chain to support the tube frame, but if desired, the pin 55 may engage the chain links 11 and 12 for this purpose. I do not wish to be limited to this latter feature.

The clutch 13 has extending inwardly therefrom a detaching pin 70 and has the underside thereof provided with a lip 71 curved downwardly and inwardly as at 72 in the usual manner. Side plates 73 of the clutch require the tube frame to rock with the clutch.

In operation, the parts are normally in the position shown in Fig. 1 with the hook over the link 12 and the clutch spaced from the tube frame. When the latter is to be removed from the chain the clutch is moved inwardly or toward the tube frame the first effect of which is to lift the latter slightly by reason of the inclined lip 72, after which the pin 70 will extend through the opening 37 and engage the hook unit. The latter is thereupon moved inwardly or to the left as viewed in Fig. 1 against the action of 45 spring 50 a sufficient distance to move the end 46 of the hook out of vertical alignment with any part of the chain. The tube frame may then be lowered in the usual manner, after which it will be returned to the chain to cause entry 50 of tongue 39 between links 11 and 12, after which the clutch moves away from the tube frame and the spring 50 restores the hook 45 to its normal holding position relatively to the chain. The loom is then ready for a repeated 55 operation with the same tube frame or a different tube frame.

During the motion of the hook relatively to the tube frame the guide pin 55 will remain in the hole 56 for all positions of the hook, thereby 60 preventing substantial angular motion of the hook around the axis of stud 47 in a plane transverse of the carrier bar. In this way the hook is always required to return to the link 12 in proper position.

75 The top 75 of the carrier bar may be slotted

as at 76 to permit the hook to move as described, the hook reaching the end of the slot while guide pin 55 is still in hole 56. The end of the carrier bar may be notched as at 77 and 78 to receive corresponding parts 79 and 80, respectively, of the ear 35 which project beyond the walls 26 and 27.

Certain parts and relationships shown herein, such as the hook member 45 located entirely on one side of the ear 35, are not claimed specifically herein but are set forth and claimed in a co-pending application filed by Robertson Serial No. 180,727.

From the foregoing it will be seen that I have provided a tube frame construction wherein the 15 ear 35 is durable and secured to the hollow block 25 which in turn is attached to the carrier bar. The ear is free from the wide slot heretofore found in similar constructions, being perforated only at 37 and 56. The hook may be wider than 20 those heretofore used due to the fact that it is not required to pass through a slot in the ear and the hook is provided with a comparatively cheap but effective slide bearing. The guide pin 55 serves to prevent angular displacement of the 25 hook relatively to the ear and may also be conveniently pressed by an operator for the purpose of manually disconnecting the tube frame from the chain at any point in the length of the latter without relying upon the clutch pin 70. Furthermore, the pin 55 may if desired be relied upon to support the tube frame when the latter is in inverted position over the chain.

Having thus described my invention it will be seen that changes and modifications may be 35 made therein by those skilled in the art without departing from the spirit and scope of the invention and I do not wish to be limited to the details herein disclosed, but what I claim is:

1. In an Axminster tube frame, a hollow carrier bar, an ear member fixed thereto and extending laterally therefrom, a supporting hook member located entirely on that side of the ear which faces the longitudinal center of the tube frame, means defining a cylindrical sliding bearing connection between the hook and carrier bar, the axis of the cylindrical bearing being substantially parallel to the axis of the carrier bar, and a guide on one member passing through the other member at a point laterally spaced from the cylindrical bearing axis to prevent substantial angular motion of the hook member around the cylindrical bearing axis.

2. In an Axminster tube frame, a hollow carrier bar, an ear fixed with respect to the end of the carrier bar and extending laterally therefrom, a supporting hook located entirely on that side of the ear which faces the longitudinal center of the carrier bar, means defining a sliding connection between the hook and the carrier bar, 60 said sliding connection being circular in cross section, and means rigid with the hook and extending through the ear at one side of said slide bearing and engaging the ear to prevent substantial angular motion of the hook in a plane transverse of the axis of said slide bearing.

3. In an Axminster tube frame, a hollow carrier bar, an ear fixed to the bar and extending laterally therefrom, a supporting hook located entirely on that side of the ear facing the longitudinal center of the tube frame, a cylindrical slide bearing connection between the hook and carrier bar, and a guide member on the hook substantially parallel to the cylindrical bearing and located at one side of the axis of the latter to pre- 75

vent substantial angular motion of the hook in a plane transverse to the cylindrical bearing axis, said guide member projecting normally through the ear to be accessible from the side of the ear opposite to the carrier bar.

5. In an Axminster tube frame, a hollow carrier bar, an ear fixed with respect to the end of the carrier bar and extending laterally therefrom, a supporting hook located entirely on that 10 side of the ear which faces the longitudinal center of the carrier bar, means defining a sliding connection between the hook and the carrier bar, said sliding connection being circular in cross section, and a guide pin secured to the hook and 15 extending through the ear and projecting outwardly beyond that face of the ear which is remote from the longitudinal center of the carrier bar to be manually accessible to be moved in a direction toward the longitudinal center of the 20 tube frame to move the hook away from the ear, said guide pin also engaging the ear to prevent substantial angular motion of the hook in a plane transverse of the axis of said sliding bearing.

25. In an Axminster loom operating with a

transporting chain, a tube frame, an ear fixed to the tube frame and extending laterally into engagement with the chain, a supporting hook movable in a direction away from the ear and toward the longitudinal center of the tube frame, said hook lying entirely on that side of the ear which faces the longitudinal center of the tube frame, means defining a slide bearing between the hook and the tube frame, said slide bearing being circular in cross section, and a guide pin secured to the hook and extending through the ear at a point under but closely adjacent to the chain when the tube frame is below the chain, said guide pin engaging the ear to prevent substantial angular motion of the hook in a plane transverse of the axis 15 of the slide bearing, said guide pin also projecting far enough beyond that face of the ear remote from the longitudinal center of the tube frame to be manually accessible for motion toward the center of the tube frame to release the 20 hook from the chain, and said guide pin also placed to engage the chain when the tube frame is over said chain to assist in supporting the tube frame on the chain.
